PAGE 2

FIG.2

FIG. 3

Fig. 1 is a front elevational view of a calculator console showing our new design.

Fig. 2 is a rear perspective view thereof; and
Fig. 3 is a front perspective view thereof.

The right side of the unit is the same as the left side, which is shown in Fig. 2. The pattern in the upper right hand portion of Fig. 3 is only partially shown, the actual arrangement being shown in Fig. 1.

The predominant features of our design reside in the portions shown in solid lines on the drawings.

We claim:

The ornamental design for a calculator console, as shown and described.
